UNITED STATES PATENT OFFICE.

GIUSEPPE BAGNANI, OF SAN FRANCISCO, CALIFORNIA.

ENDLESS DRIER FOR MACARONI.

Application filed February 15, 1926. Serial No. 88,256.

This invention relates to an endless drier for macaroni and its object is to produce a drier which will be capable of drying a considerable quantity of the material in a very short time, means being provided to pass a large quantity of air over the mass of material in the drier.

Another object of the invention is to provide wire screens for carrying the material through the machine, the air currents passing through the several screens as the material is carried along the screen.

Another object of the invention is to provide means whereby the air will be caused to pass through the material being dried as it falls from one carrier to the other, thereby insuring the even drying of the entire mass.

Another object of the invention is to provide means whereby the screens will be brushed clean to prevent the accumulation of dirt thereupon as well as to provide a series of brushes which will insure the holding of the materials under treatment on the carriers until the end of the series has been reached.

Another object of the invention is to provide means whereby the end boards of the casing enclosing the carriers may be easily taken out whenever it is necessary to examine the carriers or the materials thereon being treated.

An embodiment of the invention is shown in the accompanying drawings in which the same reference numeral is applied to the same portion throughout the several figures of the drawings and of which there may be modifications thereof.

Figure 1 is a side elevation of the complete machine, showing the chain for driving the carriers.

Figure 2 is a vertical longitudinal sectional view of the machine looking from the opposite side of the machine from Fig. 1.

Figure 3 is a view of the machine in end elevation looking toward the fan.

Figure 4 is an end elevation of the complete machine looking from the right of Figure 1, and

Figure 5 is a sectional view of one of the brush holders.

Figure 6 is a view in elevation of one of the end doors of the casing illustrating the slides which support said doors and permits them to be removed or replaced at will.

The drier consists of a casing which is supported by sills 1 and 2 extending the entire length of the machine. A floor 3 rests upon the sills 1 and 2, and there are a plurality of upright members 4 to 10 on each side of the machine which form the structure to which the side walls 11 and 12 are secured, there also being horizontal members 13 to 24 to stiffen the end panels of the casing and to stiffen the center panels near the bottom, both sides being arranged in substantially the same way. At the top there are two horizontal members 25 and 26 on each side to give the necessary stiffness to the top of the casing and the top is completely inclosed except for the end opening by the cover 27. At the end opening there is a hopper 28 through which the material is dropped upon the upper screen belt 57 extending transversely across the casing. The shafts 30 to 34 are journaled in boxes 40 to 44, mounted upon the members 20 to 24 inclusive, similar boxes being used on both sides of the casing. At the opposite end of the casing the shafts 35 to 39 are journaled in adjustable boxes 45 to 49 inclusive at both ends of the said shafts, and said boxes are adjusted by means of takeup bolts 50 to 54 inclusive, the adjustment of which is accomplished by turning the nut 55, all of which show in the two vertical end members 4, one at each side of the machine. Carried by each of the shafts 30 to 39 inclusive is a roller 56, each of said shafts having a similar roller, and around which rollers the endless screen belts pass. The endless screen belts pass around the drums 56 on each of the shafts 30, 39 and the other shafts in pairs, there being 5 endless screen belts in all, said screens being numbered 57, 58, 59, 60 and 61. On each side of the casing just below each screen, there is a groove to receive the brush bar 62, said brush bar itself having grooves to receive brushes 63, 64, the bristles of which are held in by narrow bars 65. There are 8 of the bars 62—four on each side of the casing with their bristles in contact with the lower run of the belt above them and in contact with the upper run of the belt below them. Above the top belt there is a similar slide 66 with only one set of bristles 67, which bristles engage the first belt of the series. And similarly below the lower belt 61 there is a bar 72 carrying a row of bristles 73 to clean the lower run 110

of the belt 61. The bristles on these several bars also serve to properly direct the air through and along the belts and prevent it from passing the belts at their sides. The discharge end of the casing is provided with three closures which can be taken away at will,—see 75, 76 and 77, which closures are carried by a pair of slides 78, 79 slidable into grooves that the brush bars 62 and 66 10 are slidable in and secured to each of the end members 75 to 77 inclusive, are the inclined slides 80, 81 and 82, the slides 80 and 81 having brushes as shown at 83 and 84 on their lower edges to direct the materials 15 upon the two belts 58, 60.

At the discharge end of the casing there is a discharge chute 90 in which there are a series of inclined baffles 91, and under the last belt 61 there is an inclined chute 92 20 which has a brush 93 at its upper edge to supplement the action of the brush 73 in cleaning the belt. An inclined board 94 serves to assist in closing the casing.

At one end of the casing there is the fan 25 95 on the shaft 96 journal boxes 97, 98 being provided for said shaft. A motor 99 is placed on the top of the casing and its belt 100 runs around the fan pulley 101 while the pulley 102 on the same shaft has 30 a belt 103 which runs around the pulley 104 on the shaft 105 to drive the worm 106 in mesh with the worm wheel 107. The shaft 105 is carried by two journal boxes 108, 109 and a universal joint 110 enables the worm 35 wheel casing 111 to be installed without absolute alignment with the shaft 105.

The shaft 112 which carries the worm wheel also carries a sprocket wheel 113 around which the drive chain 114 passes, 40 which extends around the drive sprockets 115 to 119 on the shafts 35 to 39.

The end of the casing over the fan is closed with a door 120, said door being carried by two slides 121 and 122 at each side of the 45 casing, the same as the slides which carry the smaller door at the opposite end of the casing, and this door also carries an inclined chute 123 which directs the materials upon the belt 59, said slide having a brush 124 at its lower edge bearing upon said belt. Be-

tween the belts 59 and 60 there is a horizontal partition 125 which has a brush at 126 bearing upon the under side of the belt 59.

The operation is as follows: Macaroni is supplied to the hopper 28 and falls on the 55 endless screen belt 57, and is carried to the end in the direction of the arrow and dropped on the belt 58 and is carried back to the other end of the casing and dropped on the belt 59 which belt drops it on belt 60 60 and from that belt to the belt 61, from belt 61 to the chute 90 and out. While the macaroni is traveling slowly through the casing a current of air is sent through and over the screen belts thoroughly drying the 65 macaroni thereon. The action of the brushes 63, 64, 67 and 73 prevents the macaroni from getting down the sides of the belts.

The motor drives the fan and the fan shaft drives the endless belts by means of a shaft, 70 worm and worm wheel, sprockets and chain.

Having thus described my invention, what I desire to secure by Letters Patent of the United States is as follows: but modifications may be made in carrying out the invention as shown in the drawings and in the above particularly described form thereof, 75 within the purview of the annexed claims.

1. An endless drier for macaroni comprising a casing, a series of endless screen belts 80 mounted therein, grooves in both sides of the casing above each belt, slides in said grooves, brushes carried by said slides and adapted to bear on the tops of said belts adjacent the edges thereof, a fan in one end of said casing 85 and means to drive said fan and said endless belts.

2. A drier of the class described comprising a rectangular casing, a series of endless screen belts mounted longitudinally in said 90 casing, longitudinal grooves in both sides of the casing above each belt, slides adapted to be inserted in said grooves the full length thereof, brush bristles adapted to be clamped in said slides by a longitudinal strip and 95 bear on said belts adjacent the edges thereof.

In testimony whereof I have hereunto set my hand this 3rd day of February, A. D. 1925.

GIUSEPPE BAGNANI.
